UNITED STATES PATENT OFFICE

WILLIAM H. MOHR, OF CHICAGO, ILLINOIS, ASSIGNOR TO ALEXANDER MOHR COMPANY, INC., OF CHICAGO, ILLINOIS, A CORPORATION OF ILLINOIS

GRIP GUIDE FOR GOLF CLUBS

Application filed September 10, 1930. Serial No. 480,896.

This invention relates to improvements in grip guides for golf clubs, and more particularly to means for guiding a player's hand into the proper position for correctly gripping the shaft of a golf club, although the invention may be utilized for many and various purposes, as, for instance, holding various types of stick-like elements, as will be apparent to one skilled in the art.

10 In the past, many and various devices have been developed for guiding the hands of a user into the correct position for holding a stick-like element such as a golf club, but, especially with regard to golf clubs, these 15 formerly known devices have, in many instances proven objectionable due to the fact that although they would permit the user to assume the proper hold upon the shaft of the club yet they also permitted the user in 20 spite of the device itself to assume an improper hold. In other words these formerly known guiding devices necessitated the user adjusting his hand to the guiding device as he would adjust his hand to the club shaft 25 in the event no guiding device was present, and with the human equation involved in the proper functioning of the device, it quite frequently happened that the user would adjust his hand to the satisfaction of the user 30 regardless of the relation of the hand and device. It may thus be seen that while devices of this character heretofore known in many instances aided in correcting a wrong grip of the club, in many other instances they 35 were susceptible of encouraging a still more incorrect grip.

The present invention has been designed to overcome the above noted as well as other defects and objections in the provision of a grip 40 guide for golf clubs which will cause a player's hand to automatically assume the proper position on the shaft of the club.

It is another object of this invention to provide a grip guide which aids to a degree not heretofore known in preventing the turning 45 of the club in the player's hands during a stroke.

Still another object of this invention is the provision of a grip guide for golf clubs and the like which causes a proper distancing of

the player's hands from the end of the shaft of the club, and results in a proper orienting of the club face.

It is still a further object of this invention to provide a golf club grip guide 55 which forces the player to embody more wrist action in his swing, increasing the wrist action up to but not in excess of the proper amount.

Still a further object of this invention is 60 the provision of a golf club grip guide which is very quickly interchangeable from one club to another and, due to suitable indicia, is readily mounted in proper position on any 65 of the clubs.

A still further object of this invention is the provision of a grip guide for golf clubs which embraces at least a portion of a user's hand, and while the device is sufficiently 70 rigid for causing the hand to properly grip the shaft of the club, yet the device is not so rigid as to cause discomfort or injury to the hand.

While some of the more salient features, characteristics and advantages of a device 75 embodying the present invention have been above pointed out, others will become apparent from the following disclosures.

The invention includes these and other features of construction and combinations of 80 parts hereinafter described and shown in a preferred form in the drawings, as more particularly indicated by the claims.

On the drawings:

Figure 1 is a fragmentary elevational view 85 of a golf club equipped with a device embodying principles of the present invention, and illustrating the use of the device.

Figure 2 is a view similar to Figure 1, 90 with the device itself shown in longitudinal section.

Figure 3 is an enlarged fragmentary view, in elevation, with parts of the device broken away, illustrating more clearly how the device is secured to the shaft of the club. 95

Figure 4 is an enlarged top plan view of the device itself as the same is seen in Figures 1, 2, and 3.

Figure 5 is a plan sectional view taken 100

substantially as indicated by the line V—V of Figure 3.

As shown on the drawings:

In the illustrated embodiment of this invention, there is shown a golf club shaft 6 upon which is mounted a device embodying principles of the present invention, this device including broadly a cup-shaped member 7 from which depends a preferably integral tubular portion 8 engaged in intimate contact with the shaft 6 when the device is mounted in proper position.

As is clearly seen in Figure 3, the shaft 6 projects through the tubular portion 8, and a suitable aperture 9 (Figure 4) in the bottom of the cup-shaped member 7, the device being readily positionable at any desired point along the shaft.

In the device itself, the cup-shaped member 7 is preferably made of a moldable material, a rubber compound being suitable since it will afford the desired rigidity and still be sufficiently flexible to prevent injury or discomfort to the hands of a user. The tubular member 8 is preferably molded integral with the member 7 but may, if so desired, be more flexible or elastic than the member 7 so that there will be no difficulty in moving the portion 8 back and forth over the head or cap normally placed on the top end of a golf club shaft. The device is designed to receive therein at least a portion of the lowermost hand of the player or club holder, but, of course, the device may be made to receive or cover a player's hand or hands to any desired extent, the illustrated embodiment of the invention showing one desirable form wherein the thumb, forefinger, and most of the second finger, of the lowermost hand 9 of the player is received within the cup member 7. Since the lodged portion of the player's hand is not movable within the member 7, obviously this member will increase the wrist action of the player in the event the player moves his wrist too little during his stroke.

The received portion of the lowermost hand 9 of the user is intimately contacted by the interior of the cup member 7 so that this hand must naturally take the proper grip on the club shaft. To accomplish this result, the interior of the member 7 is molded to fit intimately over the received portion of the hand, as is seen more clearly in Figure 4. For example, leading down to the central aperture 9 through which the shaft projects, is a thumb socket 10, and to one side of the thumb socket is another socket 11 for the knuckle of the forefinger, this socket merging into a recess 12 which accommodates the forefinger in close proximity to the club shaft. Above the recess 12 is another recess 13 for the accommodation of the second finger which will also grip the shaft above the first finger. It is apparent, therefore, that once the player's lower hand is seated within the member

7, this lower hand will automatically be caused to properly grip the golf club shaft, and with one hand properly gripping the club it is a simple matter for the player to properly grip the club with his other hand. Of course, the devices are preferably made in various sizes to accommodate variously sized hands.

It should be noted however that in thus properly positioning the hand on the shaft of a club, the hand does not grip the guide member, but the guide member engages the hand to the extent that it contacts with those portions of the thumb and fingers which are external when the hand is around the shaft and which it is to be understood are referred to where the backs of the fingers are mentioned. The result is that the hand is guided into proper position on the shaft without in any way interfering with the pressure grip of the hand around the shaft, thus leaving the player to grip with his fingers only and with any desired pressure.

In order that the guiding device may be properly mounted upon the shaft 6, the tubular portion 8 is preferably tapered in conformity to the taper of a golf club shaft. This tubular portion is held tightly around the shaft by means of a clamping member, designated generally as 14 in Figure 1, which includes a band 15 circumscribing the portion 8 and likewise tapered. One end of the band 15 is formed into a loop 16 which pivotally engages the link 17, the link in turn pivotally supporting a lever 18 having a projection 19 on the inner end thereof that engages with a detent 20 on the other end of the band. When the lever 18 is forced downwardly or toward the shaft of the club, the projection 19 is moved inwardly with a cam-like action forcing the detent 20 ahead of it and exerting a pull on the link 17, whereby the band is tightened around the tubular portion 8 to hold the same securely on the shaft in a desired position.

In using the present invention, a cup member 7 having the proper size of interior formation is selected and placed upon the shaft of a golf club until it is in the proper position. When in this position, the shaft of the club is preferably marked with a cross as indicated at 21 in Figure 3, and the cup member is then, or has been previously marked with a line as indicated at 22 in Figure 1. Therefore, when placing the device upon a club shaft, it is simply necessary to insert the end of the shaft in the tubular portion 8, until the lower edge of this portion coincides with the horizontal mark in the cross 21, and rotates the cup member 7 until the mark 22 on the portion 8 coincides with the vertical mark of the cross 21 when the device is in exactly the proper position for spacing the hand from the end of the shaft and for properly orienting the face of

the club. After the device is moved to the proper position the lever 18 of the clamping element 14 is thrown downwardly to secure the device in this position. In the event it is desired to change the device from one club to another, it is simply necessary to release the clamp 14, slip the device off the end of one club, and slide it over the end of another club, again locating the proper position 10 and clamping the device in the aforesaid manner.

From the foregoing, it will be apparent that I have provided grip guide means for golf clubs and similar stick-like elements, 15 which positively guide the hand of the user and forces this hand to assume the proper grip upon the club shaft. Moreover, the present invention is easily interchangeable from one club to another, may be made in 20 various sizes to suit various individuals, and causes no discomfort or injury through its use. It should be further noted that the utility of the present invention is not limited to student golfers but is very desirable for 25 any golfer to use in playing, in that it saves considerable time in taking proper hold of the club and also aids in very quickly assuming the proper stance. Furthermore, the present invention is light in weight, easy to 30 carry and handle, and may be very economically manufactured.

I am aware that many changes may be made, and numerous details of construction 35 may be varied through a wide range without departing from the principles of this invention, and I, therefore, do not purpose limiting the patent granted hereon, otherwise than necessitated by the prior art.

I claim as my invention:

40 1. In a device of the character described, a cup-shaped member of a moldable somewhat flexible material and internally formed to fit at least a portion of the back of the hand of a user, when clasped upon a golf 45 club shaft, said member having an axial opening and a tubular extension for engagement with a golf club shaft.

50 2. In combination with the shaft of a golf club, a guide member attached thereto presenting a concave face around the shaft toward its handle end, said face of said guide member being grooved to fit the outer contours only of the fingers of one hand and to thus position the hand on the shaft without 55 affecting the proper pressure grip of the hand on the shaft.

60 3. In combination with the shaft of a golf club, a guide member adjustable lengthwise of and around the shaft and having means engageable as a guide with external portions only of a hand placed around the shaft and against the guide member whereby to properly position the hand on the shaft without 65 affecting the gripping pressure of the hand on the shaft.

4. A hand guide for the shaft of a golf club consisting of a member secured around the shaft having guide means on its face presented toward the handle end of the shaft, said guide means engaging the backs only 70 of the lowermost fingers and thumb whereby to properly position the same without affecting the proper pressure grip of the hand on the shaft.

In testimony whereof I have hereunto sub- 75 scribed my name at Chicago, Cook County, Illinois.
